[57] CLAIM

The ornamental design for a tray package, as shown and described.

DESCRIPTION

FIG. 1 is a perspective view of a tray package showing our new design;

FIG. 2 is a top plan view thereof;

FIG. 3 is a left side elevational view thereof; the right side elevational view being a mirror image thereof;

FIG. 4 is a front elevational view thereof; the rear elevational view being a mirror image thereof;

FIG. 5 is a bottom plan view thereof; and,

FIG. 6 is a perspective view thereof, the broken line showing of tissue culture assemblies is for illustrative purpose and forms no part of the claim.
